PROCESS FOR CONVERTING HYDROCARBONS OF LOW MOLECULAR WEIGHT

Original Filed June 1, 1936

UNITED STATES PATENT OFFICE

2,270,700

PROCESS FOR CONVERTING HYDROCARBONS OF LOW MOLECULAR WEIGHT

Frederick E. Frey, Bartlesville, Okla., assignor to Phillips Petroleum Company, a corporation of Delaware.

Application June 1, 1936, Serial No. 82,954
Renewed November 7, 1939

24 Claims. (Cl. 196—10)

This invention relates to the conversion of low molecular weight hydrocarbons to hydrocarbons of high molecular weight, and more specifically to the conversion of the gaseous hydrocarbons and hydrocarbons of volatility too great for inclusion in motor fuel into normally liquid hydrocarbons suitable for motor fuel.

It has been proposed to convert normally gaseous hydrocarbons into normally liquid hydrocarbons by heating to a temperature at which reaction takes place while maintaining a high pressure and at the same time converting the less reactive hydrocarbons by pyrolyzing them at a high temperature and low pressure to produce gaseous olefins which may be mixed with the hydrocarbons subjected to the pressure conversion step.

This present invention is a continuation-in-part of my copending application Serial No. 12,981 filed March 25, 1935, which issued January 4, 1938, as Patent 2,104,296 and which in turn is a continuation-in-part of my application Serial No. 731,920 filed June 22, 1934 which issued on May 21, 1935, as Patent 2,002,394 which constitute improvements resulting in increased yield of higher molecular weight hydrocarbons and consists essentially in introducing olefin rich hydrocarbons to predominantly saturated hydrocarbons while maintaining a thermal reaction temperature level for a period of time during which reaction takes place, the olefin rich hydrocarbon being introduced to the paraffin at a plurality of times during said reaction period or continuously during said period.

The present invention has for one object an improved process for utilizing ethylene in a gas conversion process.

A further object is to provide an improved process for utilizing ethane and methane as conversion stock in conjunction with paraffins higher than ethane.

Another object is the conversion of the lower paraffins under conditions which will produce a particularly high ultimate yield of products of higher molecular weight.

Another object is the control of volatility in these products while maintaining a high ultimate yield thereof.

Another object is the effecting of economy in separating operations.

Another object is the conversion of light hydrocarbons from vapor phase oil cracking together with those from pressure still oil cracking to effect a particularly efficient conversion into motor fuel.

A still further object is the production of hydrogen.

Other objects and advantages will be apparent as the description of the process proceeds.

5 I have previously found that the simple olefins and paraffins undergo cooperative reaction when subjected to a conversion temperature under high pressure in the processes above referred to, with introduction of the olefin to the paraffin not 10 wholly before reaction, but during the course of reaction, and thereby produce a higher ultimate yield of gasoline than is obtainable in the conversion by heat and pressure of olefins and paraffins separately. The reactions taking place 15 are not fully understood, but the yield increase appears to be largely due to the direct union of paraffin and olefin molecules. The partial pressure of olefins should be low in comparison with the partial pressure of the paraffins in order 20 that the concurrent polymerization of olefin with olefin will not take place to too great an extent, yet the absolute pressure should be sufficiently high to cause synthesis reactions to predominate and to suppress considerably the splitting reactions which yield simpler gaseous hydrocarbons at the expense of higher hydrocarbons. The 25 higher the pressure the higher the ultimate yield of the normally liquid hydrocarbons which may be developed per thermal treatment without their 30 partial destruction by cracking. Increase in pressure, however, increases the rate of union of olefin with olefin and the introduction of olefin should accordingly take place at an increased 35 number of points in the reaction period or be more thinly dispersed during the reaction to obtain the maximum advantage in yield increase.

Introduction of olefin may take place thus at a plurality of points disposed along an elongated reaction tube through which the paraffin rich gases flow while a reaction temperature is maintained. Alternatively an equivalent introduction of olefin may in effect be made at fewer points or even a single point by introducing olefin to a 40 circulated stream of paraffin exposed to a reaction temperature wherein the stream passes repeatedly the point or points of olefin introduction, passing then through the thermal reaction zone and back to the point of olefin introduction. 45 A plurality of such circulating elements to each 50 of which olefin is introduced, and so arranged that the hydrocarbon stream passes through them serially may be used. In general dispersal of olefins in the paraffin is applied after the onset or during reaction. By the introduction of olefin 55 a plurality of times during the course of the

heating and reacting period, will be understood the use of any of these methods as described or their equivalents which will be obvious. The high pressure conversion may be effected in accordance with the foregoing description in either reaction chambers of enlarged cross sectional area or in tube coils and passageways of restricted cross sectional area, and the term "reaction chamber" or "reaction zone" in this connection will be understood to refer to either type of reaction vessel.

The overall conversion conditions of time and temperature for the pressure conversion steps will in general be somewhat milder than the known thermal decomposition time-temperature relationships. The temperature will vary from 800° to 1200° F., the higher temperatures being required for the conversion of the more refractory paraffins and will be readily determinable by experiment. Methane and ethane undergo reaction with added olefins with comparative difficulty, while propane, butanes and pentanes are more readily converted. The conversion temperature is not greatly dependent on the species of olefin introduced, whether ethylene, propylene, butylenes, or mixtures in which they may occur as the predominating olefins in various relative proportions. However, ethylene is the most favorably situated olefin in respect to thermodynamic driving force for paraffin-olefin union. A part of the ethylene so introduced, usually survives reaction as ethane and may be converted into unsaturated hydrocarbons by pyrolysis and returned to the pressure conversion step.

The pressure under which the pressure reaction of olefin with paraffin is conducted should in general exceed about 500 pounds per square inch. The efficiency of the paraffin-olefin reaction increases with increase of pressure, and pressures as high as 5,000-10,000 pounds per square inch and more may be used to advantage in appropriate situations, and the concentration of olefin dispersed in the paraffin, to be continuously maintained during the reaction, may be reduced accordingly, with increased efficiency as the pressure increases. A steady-state concentration of olefin is established at 10-30 per cent under 1,000 pounds pressure, depending somewhat on the identity of the paraffins and olefins reacted and the temperature and is of the order of 2 to 8 per cent at 4,000 pounds pressure with cracking reactions taking place slightly. The number of points of olefin addition may be suitably that which provides at each addition no more than and preferably much less than a quantity of olefin equal to the steady-state concentration maintained with concomitant cracking reactions, which can be readily determined by experiment. The extent of conversion into gasoline produced in one thermal treatment may be varied within wide limits, from several per cent to 30 per cent and more of the total hydrocarbon present. An attempt to react the greater part of the paraffinic hydrocarbons in a single thermal treatment however, results in degradation of a part of the gasoline formed, and it is usually desirable to react the paraffins partially, remove gasoline, and again react the paraffins with olefin. The quantity of olefin added may vary from considerably less than to more than the molal equivalent of the paraffin entering reaction while retaining the advantage of an augmented yield accompanied by more or less olefin-olefin polymerization and splitting reactions.

In the present invention, by pyrolyzing paraf-

10 fins in one stage to produce olefins and/or acetylene and by reacting paraffins in a second stage with the olefins and/or acetylene so produced, under pressure as described, higher yields of gasoline are obtainable under practical and economical conditions than can be obtained either by conversion in a single stage by heat and pressure while returning all suitable unconverted paraffins, or by pyrolyzing paraffins to produce olefins which are then polymerized by heat and pressure to produce gasoline.

15 In the simple conversion of propane, for example, by heat and pressure, the ethane produced by the thermal treatment may be pyrolyzed to produce ethylene, which is then admixed with propane and subjected to the pressure conversion step, with a resultant increase in gasoline yield. Especially if the ethylene so produced is added portionwise, or in an equivalent manner, to the 20 propane undergoing pressure conversion, in accordance with the present invention, is the gasoline yield high and the production of ethane and methane low, whereby the pyrolysis of propane at low pressure, or other hydrocarbons from an 25 extraneous source may be required to produce the volume of olefins needed for the cooperative reaction with propane. In this way a particularly high gasoline yield may be obtained, together with a reduced formation of heavy hydrocarbons of less value than gasoline.

The drawing diagrammatically illustrates one form of apparatus for carrying out the process.

30 The operation of the process should be readily understood upon consideration of the following description which is made with reference to the drawing. A conversion stock, which may be composed for the most part of paraffin hydrocarbons higher than ethane, is introduced into conduit 10 and passed therethrough to a pump 11 wherein the pressure of the charging stock is raised to a thousand pounds per square inch or more. The hydrocarbons comprising the charging stock then flow through conduit 12 from which they pass into a reaction chamber or zone 35 such as the coil 13 into which hydrocarbons rich in ethylene are introduced in a manner to be later described. Within the reaction chamber or zone such as the coil 13 thermal treatment of the mixed hydrocarbons takes place at an elevated pressure and at a temperature of 800° to 1200° F. to produce hydrocarbons of higher molecular weight. After thermally treating the hydrocarbons in this manner they pass from the coil 13 through the conduit 14 to a separator 15 in which the hydrocarbons of high molecular weight are removed and discharged through conduit 16 by which means these hydrocarbons are passed to the separator 17 wherein heavy products are separated and discharged by way of the conduit 18, controlled by the valve 19, and hydrocarbons of motor fuel boiling range are removed from the separator 17 through the conduit 20 and after being reduced to a liquid by passing through the condenser 21 are withdrawn by way of pipe 22 controlled by the valve 23. Into the separator 15 there may be introduced through the conduit 25 controlled by the valve 24 hydrocarbons containing the components intended for the conversion in this process. The hydrocarbons remaining in the separator 15, which will be predominantly normally gaseous, pass through the conduit 26 to another separator 27 in which hydrocarbons of molecular weight higher than ethane for the most part, are separated and discharged through the conduit 28 and the conduit

29, the latter being controlled by the valve 30, or these hydrocarbons so discharged from the separator 27 may be returned through the conduit 31, which is controlled by the valve 32, and returned to the conduit 10 where they are mixed with low molecular weight hydrocarbons comprising the fresh conversion stock and which together with the hydrocarbon introduced by way of conduit 31 pass through the conduit 10 to the pump 11. The lighter hydrocarbons from separator 27 which may consist mostly of methane and ethane, will pass through conduit 33 to a separator 34 in which part or all of the methane and lighter gases are separated and if desired are discharged through the conduit 35 which is controlled by the valve 36. In this manner a hydrocarbon stream, more or less predominating in ethane, is obtained which is withdrawn from the separator 34 by way of the conduit 37. The separation in the separator 34 may be effected either with the aid of low temperature which will allow the condensing of the higher hydrocarbons present, or oil absorption, or an equivalent method may be used.

The hydrocarbon which may predominate in ethane, which is withdrawn from the separator 34 by way of the conduit 37 may be discharged through conduit 38 and valve 39, or it may be passed through conduit 40 to conduit 41 wherein it may be mixed with hydrocarbons entering the system, and the mixture is then passed to a second reaction chamber or zone such as the coil 42 which may be conveniently a tube coil, wherein it is pyrolyzed at a pressure below 500 pounds per square inch, which may be as low as atmospheric or sub-atmospheric. The pyrolysis temperature within the reaction chamber or zone such as the coil 42 is above about 1,000° F. and may exceed 1,700° F. when a gas mixture particularly high in methane is supplied. The products of pyrolysis pass from the coil 42 through a conduit 43 to a separator 44 in which tar and lighter normally liquid hydrocarbons are removed or discharged through the conduit 45 controlled by the valve 46. The hydrocarbons remaining within the separator 44 will contain a substantial portion usually from 10% to 45% by volume of unsaturates of low molecular weight principally ethylene and acetylene. These latter materials will then pass through conduit 47 to a compressor 48 in which the pressures thereof are elevated sufficiently to facilitate subsequent separations and usually to a pressure of 200 to 1,000 pounds per square inch, or they may be by-passed through conduit 47A controlled by the valve 47B. The hydrocarbons are then passed through the conduit 49 to a separator 50 wherein normally liquid hydrocarbon as well as a part of the less volatile gaseous hydrocarbons may, if desired, be removed or discharged through the conduit 51, and the conduit 52 which is controlled by the valve 53. The hydrocarbons remaining in the separator 50 will then pass therefrom through the conduit 54 to a separator 55 wherein methane and lighter gases are more or less completely removed with the aid of low temperature, absorption methods, or the equivalents thereof, and discharged through conduit 56. These gases are often rich in hydrogen and constitute a source thereof. In some instances the hydrocarbons passing through conduit 10 and the pump 11 may be used to advantage as an absorbent and may be led through conduit 57 controlled by the valve 58 and introduced into the separator 55 wherein ethylene and higher boiling hydrocarbons are ab-

sorbed. The ethylene-bearing liquid is discharged from separator 55 through the conduit 59 and is carried thereby to the pump 60 and is forced thereby through the conduit 61 into the header 62 from which it flows into the conduits 63, 64, 65, 66, and 67 which are controlled by the valves 68, 69, 70, 71, and 72 respectively, and is thus introduced into the coil 13 at a plurality of points. It is to be understood that the valves 68, 69, 70, 71 and 72 which control the introduction of the ethylene-bearing liquid to the coil 13 through the pipes 63, 64, 65, 66 and 67 respectively, may be so operated as to introduce the ethylene-bearing liquid through any or all of these pipes or feasible combinations thereof, and/or these valves may be utilized merely to regulate the quantity and/or flow of the ethylene-bearing liquid so introduced to the coil 13. Reaction takes place throughout that part of the coil into which the ethylene-bearing liquid is introduced and the olefin produced is largely consumed by the reactions before the fluid passing through the coil 13 reaches a subsequent point of olefin introduction. The ethylene-rich concentrate may alternately be isolated and passed through the conduits 63, 64, 65, 66 and 67 without the presence of the absorbing medium. Hydrocarbons discharged from the separator 50 through the conduit 51 may when desired be passed through conduit 73 which is controlled by the valve 74 and passed to the separator 15 wherein the heavy hydrocarbons will be discharged with the higher molecular weight products of the higher pressure conversion step through the conduit 16.

In my process the hydrocarbons lighter than the gasoline which are discharged from conversion coil 13 will in many cases contain relatively small amounts of the lightest hydrocarbons such as result from splitting reactions. It is an object and therefore a part of my invention to effect economy in the separating operations. Accordingly a part of the hydrocarbons lighter than gasoline which pass through conduit 26 from the separator 15 may be withdrawn through the conduit 15, valve 76, cooler 77, pump 78, and passed to conduit 31 and thence through conduit 10 to the pressure reaction coil 13.

It is also an object and a part of my invention to vary and control the volatility of the liquid hydrocarbons produced, independently of the composition of conversion stock, while realizing a high yield of such liquid hydrocarbons whether they be of high or lower volatility. I have found that the lighter components of the gasoline produced, which are primarily paraffinic, may be efficiently caused to combine with simple olefins or acetylene. Thus pentanes and hexanes yield respectively heptanes and octanes when reacted with ethylene. In order to effect reduction in volatility I may return such hydrocarbons synthesized in my process to the pressure conversion coil to be reacted with simple unsaturates. Thus separator 15 may be operated in such a manner that more or less of the light gasoline hydrocarbons, otherwise discharged with the higher molecular weight products through conduit 16, pass instead through conduit 26 together with the lighter hydrocarbons, which are separated with the lighter hydrocarbons to be returned to reaction coil 13 in separator 27 and pass through conduit 28, valve 32, conduit 31, to conduit 10, and pump 11, and thence through conduit 12 to the conversion coil 13.

The unconverted gaseous hydrocarbons are of

low olefin content, usually of the order of 10% or less, and are suitable for returning to the pressure conversion as a virtually paraffinic stock for reacting again with olefin. A conversion stock such as cracking still gases containing a higher concentration of olefin may be introduced as a source of olefin for dispersing in the paraffinic stream within the reaction zone and may accompany olefins derived from low pressure pyrolysis. In such a case the fraction of olefin-depleted light hydrocarbons predominating in propane, butane and sometimes pentane, which may be separated from the effluents of the pressure conversion step, constitutes a suitable paraffinic stock for reacting with such more highly olefinic hydrocarbons.

The process is designed primarily to produce normally liquid hydrocarbons, suitable for motor fuel, which distill below about 400° F. Hydrocarbons suitable for introducing through conduit 10 to the pressure conversion step are particularly propane and the butanes and also pentanes in those cases in which the volatility they exhibit is too high for direct use as ingredients in motor fuel. Under the operating conditions given the hydrocarbons discharged from the pressure conversion effected in the reaction coil 13, boiling below the gasoline range and recycled through conduit 31, will be depleted in olefins but contain from a trace to a few per cent of ethylene, propylene, butylenes and, in some cases, pentenes.

The fresh conversion stock for the process entering through conduit 10 may either consist of the simple paraffins—propane, butane and pentane—obtained from oil distillation, natural gas or as a product of any olefin depleting prior operation applied to the volatile products of a cracking operation, or may be hydrocarbons of equivalent boiling range containing a substantial proportion of olefins such as condensate from gases derived from pressure still cracking of petroleum. Any ethylene present contributes to the yield of hydrocarbons but ethane and methane in many cases are difficultly converted in the pressure conversion step and survive to be isolated in separator 34 and passed to the pyrolysis step in coil 42. The gases subjected to the pyrolysis step in coil 42 are preferably of low olefin content and predominating in ethane, but these gases may contain more or less of higher hydrocarbons. Hydrocarbons suitable for the pyrolysis may include any of the gaseous hydrocarbons, or higher hydrocarbons, other than highly aromatic oils. They may be derived from the normally gaseous effluents of the pressure conversion operation, and from the other sources set forth, especially when the quantity available from the pressure conversion is insufficient for taking maximum advantage of the cooperative paraffin-olefin reaction. The pyrolysis may be carried out without catalyst at temperature above 1200° F. and pressures below 500 pounds per square inch under well known conditions whereby, splitting reactions are effected and unsaturated hydrocarbons, containing a more or less large proportion of ethylene are produced. Catalysts may be used to assist in the formation of such unsaturated hydrocarbons. The pyrolysis operation may produce also more or less of normally liquid hydrocarbons, but normally gaseous unsaturated hydrocarbons are at the same time obtained for reacting with paraffins under high pressure, and while a pressure below 500 pounds per square inch and temperature above about 1,000° F. lead to relatively high yields of nor-

70 mally gaseous unsaturated hydrocarbons, a higher pressure or lower temperature may be used with some sacrifice in yield of such unsaturated hydrocarbons. The method of cracking oil

known as vapor phase cracking in which such conditions are employed yields gasoline together with ethylene-rich gases which may serve as a source of olefinic reactant. Thus vapor phase cracking of oil may constitute the pyrolysis step.

Acetylene, rather than ethylene, may predominate when gaseous hydrocarbons are pyrolyzed and the pyrolysis temperature is particularly high but both are highly suitable for the process.

15 Acetylene may be produced by applying the pyrolysis to methane or other hydrocarbons at particularly high temperatures, usually above 1700° F., under well known conditions, and acetylene is particularly suitable for reaction by portionwise addition with the paraffins, the polymeric hydrocarbons so produced being largely olefinic and paraffinic, and unlike the carbon rich polymers ordinarily obtained in polymerizing acetylene. The simple polymers of acetylene 20 which may be derived from acetylene, and butadiene may also be reacted with paraffins in the same way. While methane and ethane are reacted only slowly with the olefins and in many cases are preferably not present in considerable amount in the paraffins subjected to the high pressure conversion step, they will enter into reaction more readily with acetylene, and accordingly may advantageously be present when acetylene-rich gases are introduced to the paraffinic reactants.

25 As an example of the operation of the process, propane under a pressure of 4500 pounds per square inch was reacted with ethylene produced by pyrolysis and containing a small amount of propylene, at 940° F. for 3.8 minutes, the ethylene being introduced in 40 small portions spaced throughout the reaction period. In this way an average ethylene concentration of 2.0 to 2.5 per cent by weight was maintained 30 throughout the reaction period. Seven per cent by weight of ethylene was introduced and 1.5 per cent survived unreacted. A trace of methane was formed, very small amounts of ethane, propylene and butane-butylene were produced, and 12.5 per cent by weight of normally liquid hydrocarbons, based on the quantity of propane plus ethylene thermally treated, was produced of 35 the following composition.

	Per cent by weight
55 C ₅ H ₁₀	3
1-C ₆ H ₁₂	50
n-C ₆ H ₁₂	22
C ₆ H ₁₂	2
C ₆ H ₁₄	8
60 C ₇ H ₁₄	3
C ₈ H ₁₆	
C ₇ H ₁₆	
C ₈ H ₁₈	12
Higher	Trace
	100

75 By separating the resultant ethane from the reaction products and pyrolyzing at low pressure the ethane together with added propane, ethylene, plus a small amount of propylene are produced. On reacting these olefins under 4500 pounds per square inch pressure with a molal equivalent of propane under the conditions described, liquid hydrocarbons suitable for gaso-

line are produced. A yield of 85 per cent weight of gasoline, based on the propane which serves as the sole initial conversion stock, is obtained, and this yield is significantly higher than is obtained by thermal methods previously proposed. Methane and hydrogen resulting from the pyrolysis step are virtually the sole by-products. Methane need not be introduced to the high pressure conversion step because it reacts slowly in this case. Hydrogen is preferably not introduced because it effects some loss in conversion per thermal treatment. After determining the approximate steady-state concentration of ethylene leading to efficient conversion, in the example, 2 per cent, it is evident that 4 or 5 points of olefin addition would have been sufficient in number to provide increments commensurate with and slightly less than this steady-state ethylene concentration.

I claim:

1. A process for converting hydrocarbons of low molecular weight to hydrocarbons of higher molecular weight which comprises subjecting in a first reaction zone a hydrocarbon fluid containing predominantly lower paraffins and an added quantity of acetylene to a pressure above 500 pounds per square inch and a temperature between 800° and 1200° F. consuming said paraffins and acetylene and producing hydrocarbons of higher molecular weight, subjecting in a second reaction zone gaseous hydrocarbons to a pressure below 500 pounds per square inch and a temperature above 1200° F. to form pyrolysis products, separating from the pyrolysis products a fraction rich in acetylene and introducing the said fraction into the said first reaction zone a plurality of times during the course of the passage of the hydrocarbons passing therethrough, removing from the said first reaction zone the thermally treated hydrocarbons and separating therefrom the hydrocarbons of higher molecular weight produced.

2. A process for producing gasoline boiling range hydrocarbons from predominantly paraffinic hydrocarbons, which comprises passing normally gaseous predominantly paraffinic hydrocarbons through a first reaction zone and therein subjecting said hydrocarbons to a pressure less than 500 pounds per square inch and to a reaction temperature for a period of time sufficient to produce normally gaseous unsaturated hydrocarbons of the class consisting of normally gaseous olefins, acetylenes, and butadiene, passing a portion of the effluents of said first reaction zone containing said normally gaseous unsaturated hydrocarbons to a separating zone, compressing a mixture of predominantly paraffinic hydrocarbons of not less than three nor more than six carbon atoms per molecule to a pressure in excess of 500 pounds per square inch and subjecting a portion of said mixture in a second reaction zone to a temperature of 800° to 1200° F. causing reaction to take place consuming paraffins and subsequently added unsaturated hydrocarbons, passing a further portion of said mixture to said separating zone as an absorbent liquid and absorbing therein normally gaseous unsaturated hydrocarbons produced in said first reaction zone, and introducing the resultant mixture in amounts not to exceed thirty per cent of unsaturated hydrocarbons present in the resultant mixture to said second reaction zone a plurality of times during the course of the passage of the hydrocarbons passing therethrough.

3. A process for converting hydrocarbon mixtures of low molecular weight predominating in paraffin hydrocarbons into higher molecular weight hydrocarbons, which comprises compressing a predominantly paraffinic normally gaseous hydrocarbon mixture to a pressure between 500 and 5000 pounds per square inch and subjecting a portion of said mixture in a first reaction zone to a temperature of 800° to 1200° F., passing a further portion of said mixture as an absorbent fluid to a separating zone and introducing a hydrocarbon mixture containing normally gaseous unsaturated hydrocarbons of the class consisting of normally gaseous olefins, acetylenes, and butadiene produced in a second reaction zone to said separating zone, absorbing said normally gaseous unsaturated hydrocarbons in said absorbent fluid and introducing the resultant mixture into said first reaction zone 20 a plurality of times during the course of the passage of the hydrocarbons passing therethrough in amounts not to exceed 2 to 10 per cent of unsaturated hydrocarbons in the resultant mixture, separating from the effluents of said first reaction zone a fraction containing higher molecular weight hydrocarbons so produced, separating a fraction containing normally gaseous hydrocarbons and passing said fraction to said second reaction zone and therein subjecting normally gaseous hydrocarbons to a temperature in excess of 1200° F. while under a pressure less than 500 pounds per square inch for a period of time such that an optimum yield of normally gaseous unsaturated hydrocarbons of the class consisting of normally gaseous olefins, acetylenes, and butadiene are produced, and passing said unsaturated hydrocarbons to the aforesaid separating zone.

4. A process for converting hydrocarbons of low molecular weight into a motor fuel of low and controlled volatility, which comprises introducing to a process an initial hydrocarbon mixture comprised predominantly of paraffin hydrocarbons of not less than three and not more than five carbon atoms per molecule, adding thereto a recycle hydrocarbon mixture comprised of predominantly paraffin hydrocarbons of not less than three nor more than six carbon atoms per molecule, subjecting a first portion of said added mixtures in a first reaction zone to a pressure of between 500 and 10,000 pounds per square inch and to a temperature of between 800° and 1200° F., concomitantly subjecting a normally gaseous hydrocarbon mixture in a second reaction zone to a pyrolysis temperature in excess of 1200° F. while under a pressure less than 500 pounds per square inch for a period of time sufficient to produce normally gaseous unsaturated hydrocarbons of the class consisting of normally gaseous olefins, acetylenes, and butadiene, passing a portion of the effluents of said reaction zone containing said normally gaseous unsaturated hydrocarbons to a separating zone, passing a second portion of said added mixtures as an absorbent fluid to said separating zone whereby normally gaseous unsaturated hydrocarbons are absorbed in said fluid, adding to said portion of added mixtures in said first reaction zone said normally gaseous unsaturated hydrocarbons and said absorbent fluid in a manner such that the total concentration of unsaturated hydrocarbons does not exceed about 30 per cent in said first reaction zone, separating from the effluents of said first reaction zone a first 50 fraction comprised of a gasoline boiling range

5. A process for converting hydrocarbons of low molecular weight into a motor fuel of low and controlled volatility, which comprises introducing to a process an initial hydrocarbon mixture comprised predominantly of paraffin hydrocarbons of not less than three and not more than five carbon atoms per molecule, adding thereto a recycle hydrocarbon mixture comprised of predominantly paraffin hydrocarbons of not less than three nor more than six carbon atoms per molecule, subjecting a first portion of said added mixtures in a first reaction zone to a pressure of between 500 and 10,000 pounds per square inch and to a temperature of between 800° and 1200° F., concomitantly subjecting a normally gaseous hydrocarbon mixture in a second reaction zone to a pyrolysis temperature in excess of 1200° F. while under a pressure less than 500 pounds per square inch for a period of time sufficient to produce normally gaseous unsaturated hydrocarbons of the class consisting of normally gaseous olefins, acetylenes, and butadiene, passing a portion of the effluents of said reaction zone containing said normally gaseous unsaturated hydrocarbons to a separating zone, passing a second portion of said added mixtures as an absorbent fluid to said separating zone whereby normally gaseous unsaturated hydrocarbons are absorbed in said fluid, adding to said portion of added mixtures in said first reaction zone said normally gaseous unsaturated hydrocarbons and said absorbent fluid in a manner such that the total concentration of unsaturated hydrocarbons does not exceed about 30 per cent in said first reaction zone, separating from the effluents of said first reaction zone a first 55 fraction comprised of a gasoline boiling range

6. A process for converting hydrocarbons of low molecular weight into a motor fuel of low and controlled volatility, which comprises introducing to a process an initial hydrocarbon mixture comprised predominantly of paraffin hydrocarbons of not less than three and not more than five carbon atoms per molecule, adding thereto a recycle hydrocarbon mixture comprised of predominantly paraffin hydrocarbons of not less than three nor more than six carbon atoms per molecule, subjecting a first portion of said added mixtures in a first reaction zone to a pressure of between 500 and 10,000 pounds per square inch and to a temperature of between 800° and 1200° F., concomitantly subjecting a normally gaseous hydrocarbon mixture in a second reaction zone to a pyrolysis temperature in excess of 1200° F. while under a pressure less than 500 pounds per square inch for a period of time sufficient to produce normally gaseous unsaturated hydrocarbons of the class consisting of normally gaseous olefins, acetylenes, and butadiene, passing a portion of the effluents of said reaction zone containing said normally gaseous unsaturated hydrocarbons to a separating zone, passing a second portion of said added mixtures as an absorbent fluid to said separating zone whereby normally gaseous unsaturated hydrocarbons are absorbed in said fluid, adding to said portion of added mixtures in said first reaction zone said normally gaseous unsaturated hydrocarbons and said absorbent fluid in a manner such that the total concentration of unsaturated hydrocarbons does not exceed about 30 per cent in said first reaction zone, separating from the effluents of said first reaction zone a first 60 fraction comprised of a gasoline boiling range

7. A process for converting hydrocarbons of low molecular weight into a motor fuel of low and controlled volatility, which comprises introducing to a process an initial hydrocarbon mixture comprised predominantly of paraffin hydrocarbons of not less than three and not more than five carbon atoms per molecule, adding thereto a recycle hydrocarbon mixture comprised of predominantly paraffin hydrocarbons of not less than three nor more than six carbon atoms per molecule, subjecting a first portion of said added mixtures in a first reaction zone to a pressure of between 500 and 10,000 pounds per square inch and to a temperature of between 800° and 1200° F., concomitantly subjecting a normally gaseous hydrocarbon mixture in a second reaction zone to a pyrolysis temperature in excess of 1200° F. while under a pressure less than 500 pounds per square inch for a period of time sufficient to produce normally gaseous unsaturated hydrocarbons of the class consisting of normally gaseous olefins, acetylenes, and butadiene, passing a portion of the effluents of said reaction zone containing said normally gaseous unsaturated hydrocarbons to a separating zone, passing a second portion of said added mixtures as an absorbent fluid to said separating zone whereby normally gaseous unsaturated hydrocarbons are absorbed in said fluid, adding to said portion of added mixtures in said first reaction zone said normally gaseous unsaturated hydrocarbons and said absorbent fluid in a manner such that the total concentration of unsaturated hydrocarbons does not exceed about 30 per cent in said first reaction zone, separating from the effluents of said first reaction zone a first 65 fraction comprised of a gasoline boiling range

8. A process for converting hydrocarbons of low molecular weight into a motor fuel of low and controlled volatility, which comprises introducing to a process an initial hydrocarbon mixture comprised predominantly of paraffin hydrocarbons of not less than three and not more than five carbon atoms per molecule, adding thereto a recycle hydrocarbon mixture comprised of predominantly paraffin hydrocarbons of not less than three nor more than six carbon atoms per molecule, subjecting a first portion of said added mixtures in a first reaction zone to a pressure of between 500 and 10,000 pounds per square inch and to a temperature of between 800° and 1200° F., concomitantly subjecting a normally gaseous hydrocarbon mixture in a second reaction zone to a pyrolysis temperature in excess of 1200° F. while under a pressure less than 500 pounds per square inch for a period of time sufficient to produce normally gaseous unsaturated hydrocarbons of the class consisting of normally gaseous olefins, acetylenes, and butadiene, passing a portion of the effluents of said reaction zone containing said normally gaseous unsaturated hydrocarbons to a separating zone, passing a second portion of said added mixtures as an absorbent fluid to said separating zone whereby normally gaseous unsaturated hydrocarbons are absorbed in said fluid, adding to said portion of added mixtures in said first reaction zone said normally gaseous unsaturated hydrocarbons and said absorbent fluid in a manner such that the total concentration of unsaturated hydrocarbons does not exceed about 30 per cent in said first reaction zone, separating from the effluents of said first reaction zone a first 70 fraction comprised of a gasoline boiling range

9. A process for converting hydrocarbons of low molecular weight into a motor fuel of low and controlled volatility, which comprises introducing to a process an initial hydrocarbon mixture comprised predominantly of paraffin hydrocarbons of not less than three and not more than five carbon atoms per molecule, adding thereto a recycle hydrocarbon mixture comprised of predominantly paraffin hydrocarbons of not less than three nor more than six carbon atoms per molecule, subjecting a first portion of said added mixtures in a first reaction zone to a pressure of between 500 and 10,000 pounds per square inch and to a temperature of between 800° and 1200° F., concomitantly subjecting a normally gaseous hydrocarbon mixture in a second reaction zone to a pyrolysis temperature in excess of 1200° F. while under a pressure less than 500 pounds per square inch for a period of time sufficient to produce normally gaseous unsaturated hydrocarbons of the class consisting of normally gaseous olefins, acetylenes, and butadiene, passing a portion of the effluents of said reaction zone containing said normally gaseous unsaturated hydrocarbons to a separating zone, passing a second portion of said added mixtures as an absorbent fluid to said separating zone whereby normally gaseous unsaturated hydrocarbons are absorbed in said fluid, adding to said portion of added mixtures in said first reaction zone said normally gaseous unsaturated hydrocarbons and said absorbent fluid in a manner such that the total concentration of unsaturated hydrocarbons does not exceed about 30 per cent in said first reaction zone, separating from the effluents of said first reaction zone a first 75 fraction comprised of a gasoline boiling range

hydrocarbon mixture of a low and controlled volatility and removing it from the process, separating a second fraction comprised of predominantly paraffin hydrocarbons of not less than three nor more than six carbon atoms per molecule and containing controlled amounts of hydrocarbons of five and six carbon atoms per molecule and returning said fraction to said first reaction zone as said recycle hydrocarbon mixture, and further separating a third fraction of a lower average molecular weight than said second fraction and passing said third fraction to said second reaction zone.

5. A process for producing gasoline boiling range hydrocarbons from predominantly paraffinic hydrocarbons, which comprises passing predominantly paraffinic hydrocarbons through a first reaction zone and therein subjecting said hydrocarbons to a treatment under a pressure less than 500 pounds per square inch and to a reaction temperature in excess of 1000° F., for a period of time sufficient to produce normally gaseous unsaturated hydrocarbons of the class consisting of normally gaseous olefins, acetylenes, and butadiene, passing at least a portion of the effluents of said first reaction zone containing said normally gaseous unsaturated hydrocarbons to a separating zone, introducing to said process a mixture of predominantly paraffinic hydrocarbons of not less than three nor more than six carbon atoms per molecule, compressing at least a portion of said mixture to a pressure between 500 and 10,000 pounds per square inch and subjecting said compressed mixture in a second reaction zone to a temperature between 800° and 1200° F., causing reaction to take place consuming paraffins and subsequently added unsaturated hydrocarbons, passing a further portion of said mixture to said separating zone under a suitable pressure as an absorbent liquid and absorbing therein normally gaseous unsaturated hydrocarbons of the class consisting of normally gaseous olefins, acetylenes, and butadiene and introducing the resultant mixture under a pressure between 500 and 10,000 pounds per square inch and in amounts not to exceed thirty per cent of unsaturated hydrocarbons in the reaction mixture to said second reaction zone a plurality of times during the course of the passage of the hydrocarbons passing therethrough, and finally passing a hydrocarbon stream from said second reaction zone to a separating zone and separating therefrom gasoline boiling range hydrocarbons.

6. A process for converting paraffin hydrocarbons of two or more carbon atoms per molecule to gasoline boiling hydrocarbons of controlled volatility, which comprises subjecting predominantly paraffin hydrocarbons admixed with normally gaseous unsaturated hydrocarbons of the class consisting of normally gaseous olefins, acetylenes, and butadiene in such a manner that the total concentration of unsaturates in the mixture at any one time does not exceed 30% to a temperature between 800 and 1200° F., and a pressure greater than 500 pounds per square inch to effect conversion to predominantly saturated hydrocarbons of higher molecular weight, separating a fraction from the effluent of said conversion step containing predominantly paraffin hydrocarbons of not less than two carbon atoms per molecule and containing controlled amounts of predominantly paraffin hydrocarbons of from five to six carbon atoms per molecule, and admixing said fraction with the fresh charge entering the conversion step.

7. A process for reacting paraffin hydrocarbons with unsaturated hydrocarbons to produce predominantly paraffinic products of higher molecular weight including gasoline boiling range hydrocarbons of controlled volatility which comprises charging a predominantly paraffinic hydrocarbon mixture of between 2 and 6 carbon atoms per molecule to a reaction zone, admixing therewith unsaturated normally gaseous hydrocarbons of the class consisting of normally gaseous olefins, acetylenes, and butadiene in such quantity that the total concentration of unsaturates in the reaction mixture at no time exceeds 30%, maintaining a reaction pressure exceeding 500 pounds per square inch and a reaction temperature between 800 and 1200° F., in said zone to produce predominantly paraffinic reaction products, fractionating said products to recover a light fraction and a heavier fraction, the light fraction containing hydrocarbons of 5 and 6 carbon atoms per molecule in controlled amounts, recycling said light fraction to the reaction zone to increase the quantity of paraffinic products of 7 and more carbon atoms per molecule in the products of the reaction step.
8. A process for converting hydrocarbons of low molecular weight into hydrocarbons of higher molecular weight, which comprises subjecting in a first reaction zone a predominantly paraffinic hydrocarbon fluid composed of hydrocarbons of not more than six carbon atoms per molecule and added normally gaseous unsaturated hydrocarbons of the class consisting of normally gaseous olefins, acetylenes, and butadiene to a pressure above 500 pounds per square inch and a temperature between 800° and 1200° F. for a period of time wherein reaction takes place consuming said paraffins and unsaturated hydrocarbons, said added unsaturated hydrocarbons being added in a total amount between 2 and 30 per cent by weight, subjecting in a second reaction zone a hydrocarbon material to a pyrolysis temperature above 1200° F. at a pressure less than 500 pounds per square inch for a period of time such that an optimum yield of normally gaseous unsaturated hydrocarbons of the class consisting of normally gaseous olefins, acetylenes, and butadiene are produced, introducing said unsaturated hydrocarbons so produced, as being at least a portion of said first added unsaturated hydrocarbons, into said first reaction zone at a plurality of points during the period of time wherein reaction takes place, separating from the effluents of said first reaction zone a first fraction consisting of the heavier of the hydrocarbons of higher molecular weight so produced and removing it from the process, also separating a second fraction containing at least a portion of the lighter of the hydrocarbons of higher molecular weight so produced and passing said fraction to said first reaction zone.
9. A process for converting hydrocarbons of low molecular weight into a motor fuel of low and controlled volatility which comprises introducing to a process an initial hydrocarbon mixture comprised predominantly of paraffin hydrocarbons of not less than three and not more than five carbon atoms per molecule, adding thereto a recycle hydrocarbon mixture comprised of predominantly paraffin hydrocarbons of not less than three nor more than six carbon atoms per molecule, subjecting said combined mixtures in a first reaction zone to a pressure of between 500 and 10,000 pounds per square inch and to a temperature of between 800° and 1200° F., concomitantly

tantly subjecting a normally gaseous hydrocarbon mixture in a second reaction zone to a pyrolysis temperature in excess of 1200° F. while under a pressure less than 500 pounds per square inch, for a period of time sufficient to produce normally gaseous unsaturated hydrocarbons of the class consisting of normally gaseous olefins, acetylenes, and butadiene, adding to said mixture in said first reaction zone said normally gaseous unsaturated hydrocarbons from said second reaction zone in a manner such that the total concentration of unsaturated hydrocarbons does not exceed about 30 per cent, separating from the effluents of said first reaction zone a first fraction comprised of a gasoline boiling range hydrocarbon mixture of a low and controlled volatility and removing it from the process, separating a second fraction comprised of predominantly paraffin hydrocarbons of not less than three nor more than six carbon atoms per molecule and containing controlled amounts of hydrocarbons of five and six carbon atoms per molecule and returning said fraction to said first reaction zone as said recycle hydrocarbon mixture, and further separating a third fraction of a lower average molecular weight than said second fraction and passing said third fraction to said second reaction zone.

10. A process for converting paraffin hydrocarbons of low molecular weight into higher molecular weight hydrocarbons, which comprises passing predominantly paraffinic hydrocarbons which are predominantly ethane and propane through a first reaction zone and therein subjecting said hydrocarbons to a treatment under a pressure less than 500 pounds per square inch and to a reaction temperature in excess of 1000° F. for a period of time sufficient to produce a substantial amount of ethylene, passing at least a portion of the effluents of said first reaction zone containing said ethylene to a separating zone, introducing to said process a paraffin hydrocarbon material of not less than three nor more than six carbon atoms per molecule, compressing at least a portion of said hydrocarbon material to a pressure between 1,000 and 10,000 pounds per square inch and subjecting said compressed material in a second reaction zone to a temperature between 800° and 1200° F. causing reaction to take place consuming said hydrocarbon material and subsequently added ethylene, passing a further portion of said hydrocarbon material to said separating zone under a suitable pressure as an absorbent liquid and absorbing therein ethylene, introducing at least a portion of the resultant mixture under a pressure between 1,000 and 10,000 pounds per square inch and in an amount between about two and about ten per cent by weight of ethylene in the reaction mixture to said second reaction zone a plurality of times during the course of the passage of the hydrocarbons passing therethrough, and finally passing a hydrocarbon stream from said second reaction zone to a separating zone and separating therefrom a fraction containing gasoline boiling range hydrocarbons.

11. In a process for the production of higher boiling hydrocarbons from lower boiling hydrocarbons, the step which consists in adding to a stream of predominantly saturated hydrocarbons, maintained at a conversion temperature and pressure, successive small quantities of predominantly acetylenic hydrocarbons, in such amount that the content of added acetylenes in the mixture

at no time exceeds 10 per cent by weight of the total hydrocarbons present.

12. A process for producing normally liquid hydrocarbon mixtures in the gasoline boiling range, comprising heating a stream of predominantly saturated hydrocarbons to a reaction temperature under pressures in excess of 500 pounds per square inch, adding acetylene-containing hydrocarbons to the said stream at a plurality of points, the said points being so spaced as to allow appreciable reaction to take place before the subsequent addition of further acetylene, and maintaining the content of added acetylene in the mixture at not more than 10 per cent by weight of the hydrocarbons present therein.

13. A process for producing hydrocarbon mixtures containing at least 50 per cent of saturated hydrocarbons, which comprises heating a stream of predominantly saturated hydrocarbons to a decomposition temperature under a pressure in excess of approximately 4,000 pounds per square inch, adding acetylene-containing hydrocarbons to the said stream at a plurality of points, while maintaining the concentration of added acetylenes in the resulting mixture at about 2 per cent by weight and separating the products from the unreacted hydrocarbons.

14. A process for the production of higher boiling hydrocarbons from lower boiling hydrocarbons of at least 2 carbon atoms per molecule which comprises adding to a stream of predominantly saturated hydrocarbons, maintained at a conversion temperature and pressure, acetylenic hydrocarbons in such a manner and in such amounts that the concentration of acetylenic hydrocarbons in the resultant mixture undergoing reaction at no time exceeds 10 per cent by weight.

15. The process claimed in claim 14 in which the concentration of acetylenic hydrocarbons is about 2 per cent.

16. A process for the production of higher boiling hydrocarbons from lower boiling hydrocarbons of at least 2 carbon atoms per molecule which comprises adding to a stream of predominantly saturated hydrocarbons, maintained at a reaction temperature between 800° and 1200° F. and a pressure of between 500 and 10,000 pounds per square inch, acetylenic hydrocarbons in such a manner and in such amounts that the concentration of acetylenic hydrocarbons in the resultant mixture undergoing reaction at no time exceeds 10 per cent by weight.

17. A process for converting paraffin hydrocarbons of low molecular weight into higher molecular weight hydrocarbons which comprises passing predominantly paraffinic hydrocarbons through a first reaction zone and therein subjecting said hydrocarbons to a pressure less than 500 pounds per square inch and a reaction temperature in excess of 1000° F. for period of time sufficient to produce normally gaseous unsaturated hydrocarbons of the class consisting of normally gaseous olefins, acetylenes, and butadiene, passing at least a portion of the effluents from said first reaction zone containing normally gaseous unsaturated hydrocarbons so produced to a separating zone, introducing a paraffin hydrocarbon material of not less than 2 nor more than 6 carbon atoms per molecule to said separating zone in liquid phase and under a suitable pressure to absorb therein normally gaseous unsaturated hydrocarbons from said portion of the effluents from said first reaction zone and introducing the resultant mixture into a body of predominantly paraffin hydrocarbons.

carbons maintained at a reaction temperature and pressure suitable for the conversion reaction in such a manner that the concentration of unsaturated hydrocarbons in the resultant mixture undergoing conversion does not exceed 10 per cent by weight.

18. A process for producing gasoline boiling range hydrocarbons from predominantly paraffinic hydrocarbons, which comprises passing normally gaseous predominantly paraffinic hydrocarbons through a first reaction zone and therein subjecting said hydrocarbons to a pressure less than 500 pounds per square inch into a reaction temperature for a period of time sufficient to produce normally gaseous olefin hydrocarbons, passing a portion of the effluents of said first reaction zone containing said normally gaseous olefin hydrocarbons to a separating zone, compressing a mixture of predominantly paraffinic hydrocarbons of not less than 3 nor more than 6 carbon atoms per molecule to a pressure in excess of 500 pounds per square inch and subjecting a portion of said mixture in a second reaction zone to a temperature of 800 to 1200° F., causing reaction to take place consuming paraffins and subsequently added olefin hydrocarbons, passing a further portion of said mixture to said separating zone as an absorbent liquid and absorbing therein normally olefin hydrocarbons produced in said first reaction zone, and introducing the resultant mixture in amounts not to exceed 30% of olefin hydrocarbons in the resultant mixture to said second reaction zone a plurality of times during the course of a passage of hydrocarbons passing therethrough.

19. A process for converting hydrocarbons of low molecular weight into a motor fuel of low and controlled volatility, which comprises introducing to a process an initial hydrocarbon mixture comprised predominantly of paraffin hydrocarbons of not less than 3 and not more than 5 carbon atoms per molecule, adding thereto a recycle mixture comprised of predominantly paraffin hydrocarbons of not less than 3 nor more than 6 carbon atoms per molecule, subjecting a first portion of said added mixtures in a first reaction zone to a pressure of between 500 and 10,000 pounds per square inch and to a temperature of between 800 and 1200° F., concomitantly subjecting a normally gaseous hydrocarbon mixture in a second reaction zone to a pyrolysis temperature in excess of 1200° F. while under a pressure less than 500 pounds per square inch for a period of time sufficient to produce normally gaseous olefin hydrocarbons, passing a portion of the effluents of said second reaction zone containing said normally gaseous olefin hydrocarbons to a separating zone, passing a second portion of said added mixtures as an absorbent liquid to said separating zone whereby normally gaseous olefin hydrocarbons are absorbed in said liquid, adding to said portion of added mixture in said first reaction zone said normally gaseous olefin hydrocarbons and said absorbent liquid in a manner such that the total concentration of olefin hydrocarbons does not exceed about 10% in said first reaction zone, separating from the effluents of said first reaction zone a first fraction comprised of a gasoline boiling range hydrocarbon mixture of a low and controlled volatility and removing it from the process, separating a second fraction comprised of predominantly paraffin hydrocarbons of not less than 3 nor more than 6 carbon atoms per molecule and containing controlled amounts of hydrocarbons

5 of 5 and 6 carbon atoms per molecule and returning said fraction to said first reaction zone as said recycled hydrocarbon mixture, and further separating a third fraction of a lower average molecular weight than said second fraction and passing said third fraction to said second reaction zone.

20. A process for producing gasoline boiling range hydrocarbons from predominantly paraffinic hydrocarbons, which comprises passing predominantly paraffinic hydrocarbons through a first reaction zone and therein subjecting said hydrocarbons to a treatment under a pressure less than 500 pounds per square inch and to a reaction temperature in excess of 1,000° F., for a period of time sufficient to produce normally gaseous olefin hydrocarbons, passing at least a portion of the effluents of said first reaction zone containing said normally gaseous olefin hydrocarbons to a separating zone, introducing to said process a mixture of predominantly paraffinic hydrocarbons of not less than 3 nor more than 6 carbon atoms per molecule, compressing at least a portion of said mixture to a pressure of between 500 and 10,000 pounds per square inch and subjecting said compressed mixture in a second reaction zone to a temperature between 800 and 1200° F., causing reaction to take place consuming paraffins and subsequently added olefin hydrocarbons, passing a further portion of said mixture to said separating zone under a suitable pressure as an absorbent liquid and absorbing therein normally gaseous olefin hydrocarbons produced in said first reaction zone, and introducing the resultant mixture under a pressure between 500 and 10,000 pounds per square inch and in amounts not to exceed 2 to 10% of olefin hydrocarbons in the reaction mixture to said second reaction zone a plurality of times during the course of the passage of the hydrocarbons passing therethrough, and finally passing a hydrocarbon stream from said second reaction zone to a separating zone and separating therefrom gasoline boiling range hydrocarbons.

21. A process for converting paraffin hydrocarbons of 2 or more carbon atoms per molecule to gasoline boiling range hydrocarbons of controlled volatility, which comprises subjecting predominantly paraffin hydrocarbons admixed with normally gaseous olefin hydrocarbons in such a manner that the total concentration of olefins in the mixture at any one time does not exceed about 10% to a temperature between 800 and 1200° F., and a pressure greater than 500 pounds per square inch to effect conversion to predominantly saturated hydrocarbons of higher molecular weight, separating a fraction from the effluent of said conversion step containing predominantly paraffin hydrocarbons of not less than 2 carbon atoms per molecule and containing controlled amounts of predominantly paraffin hydrocarbons of from 5 to 6 carbon atoms per molecule, and admixing said fraction with the fresh charge entering the conversion step.

22. A process for reacting paraffin hydrocarbons with olefin hydrocarbons to produce predominantly paraffinic products of higher molecular weight including gasoline boiling range hydrocarbons of controlled volatility, which comprises charging a predominantly paraffinic hydrocarbon mixture of between 2 and 6 carbon atoms per molecule to a reaction zone, admixing therewith olefinic normally gaseous hydrocarbons in such quantity that the total concentrations of olefins in the reaction mixture at no

time exceeds about 10%, maintaining a reaction pressure exceeding 500 pounds per square inch and a reaction temperature between 800 and 1200° F. in said zone to produce predominantly paraffinic reaction products, fractionating said products to recover a light fraction and a heavier fraction, the light fraction containing hydrocarbons of 5 and 6 carbon atoms per molecule in controlled amounts, recycling said light fraction to the reaction zone to increase the quantity of paraffinic products of 7 and more carbon atoms per molecule in the products of the reaction step.

23. A process for converting hydrocarbons of low molecular weight into hydrocarbons of higher molecular weight, which comprises subjecting in a first reaction zone a predominantly paraffinic hydrocarbon fluid composed of hydrocarbons of not more than 6 carbon atoms per molecule and added normally gaseous olefin hydrocarbons to a pressure above 500 pounds per square inch and a temperature between 800 and 1200° F. for a period of time wherein reaction takes place consuming said paraffins and olefin hydrocarbons, said added olefin hydrocarbons being added in a total amount between 2 and 30% by weight, subjecting in a second reaction zone a hydrocarbon material to a pyrolysis temperature above 1200° F. at a pressure less than 500 pounds per square inch for a period of time such that normally gaseous olefin hydrocarbons are produced, introducing said olefin hydrocarbons so produced, as being at least a portion of said first added olefin hydrocarbons, into said first reaction zone at a plurality of points during the period of time wherein the reaction takes place, separating from the effluents of said first reaction zone a first fraction consisting of the heavier of the hydrocarbons of higher molecular weight so produced and removing it from the process, also separating a second fraction containing at least a portion of the lighter of the hydrocarbons of higher molecular weight so produced and passing said fraction to said first reaction zone.

24. A process for converting hydrocarbons of low molecular weight into a motor fuel of low and controlled volatility, which comprises introducing to a process an initial hydrocarbon mixture comprised predominantly of paraffin hydrocarbons of not less than 3 and not more than 5 carbon atoms per molecule, adding thereto a recycle hydrocarbon mixture comprised of predominantly paraffin hydrocarbons of not less than 3 nor more than 6 carbon atoms per molecule, subjecting said combined mixtures in a first reaction zone to a pressure of between 500 and 10,000 pounds per square inch and to a temperature of between 800 and 1200° F., concomitantly subjecting a normally gaseous hydrocarbon mixture in a second reaction zone to a pyrolysis temperature in excess of 1200° F. while under a pressure less than 500 pounds per square inch for a period of time sufficient to produce normally gaseous olefin hydrocarbons, adding to said mixture in said first reaction zone said normally gaseous olefin hydrocarbons from said second reaction zone in a manner such that the total concentration of olefin hydrocarbons is between about 2 and 10%, separating from the effluents of said first reaction zone a first fraction comprised of a gasoline boiling range hydrocarbon mixture of a low and controlled volatility and removing it from the process, separating a second fraction comprised of predominantly paraffin hydrocarbons of not less than 3 nor more than 6 carbon atoms per molecule and containing controlled amounts of hydrocarbons of 5 and 6 carbon atoms per molecule and returning said fraction to said first reaction zone as said recycle hydrocarbon mixture, and further separating the third fraction of a lower average molecular weight than said second fraction and passing said third fraction to said second reaction zone.

FREDERICK E. FREY.

CERTIFICATE OF CORRECTION.

Patent No. 2,270,700.

January 20, 1942.

FREDERICK E. FREY.

It is hereby certified that error appears in the printed specification of the above numbered patent requiring correction as follows: Page 8, first column, line 28, claim 18, after the word "normally" insert --gaseous--; and that the said Letters Patent should be read with this correction therein that the same may conform to the record of the case in the Patent Office.

Signed and sealed this 24th day of March, A. D. 1942.

(Seal)

Henry Van Arsdale,
Acting Commissioner of Patents.
